GOBLET

Frank R. Helms, Moundsville, W. Va., assignor to
Fostoria Glass Company, Moundsville, W. Va.,
a corporation of West Virginia

Application November 26, 1948, Serial No. 149,827

Term of patent 14 years

(Cl. D36—8)

To all whom it may concern:

Be it known that I, Frank R. Helms, a citizen of the United States of America, residing at Moundsville, in the county of Marshall and State of West Virginia, have invented a new, original, and ornamental Design for a Goblet, of which the following is a specification, reference being had to the accompanying drawing, forming a part thereof, wherein:

The single figure is a side elevational view of a goblet, showing my new design.

The goblet is circular and the dominant feature of the instant invention resides in the surface ornamentation shown in full lines, which is repeated around the peripheral surface.

I claim:

The ornamental design for a goblet, as shown and described.

FRANK R. HELMS.
